UNITED STATES PATENT OFFICE.

HOWARD H. DOUGLASS, OF LOS ANGELES, CALIFORNIA.

SPRING COMPRESSOR.

Application filed January 26, 1921. Serial No. 440,202.

To all whom it may concern:

Be it known that I, HOWARD H. DOUGLASS, a citizen of the United States, residing at Los Angeles, in the county of Los Angeles 5 and State of California, have invented new and useful Improvements in Spring Compressors, of which the following is a specification.

It is the object of this invention to provide an apparatus whereby coil springs such as are employed in shock absorbers for automobiles may be readily compressed.

The invention will be readily understood from the following description of the accompanying drawings, in which—

Figure 1 is a perspective view of the apparatus in use.

Fig. 2 is a transverse section on the line 2—2 of Fig. 1.

Fig. 3 is a plan view of a portion of the spring compressor showing the spring to be compressed.

Fig. 4 is a plan view of the plate secured to the spring so as to retain the latter in its compressed position.

Fig. 5 is a fragmentary perspective view of the base for supporting the spring while it is being compressed.

Fig. 6 is a side elevation of the supporting base and spring showing the method of mounting the same upon the base when the spring is attached to its usual supporting bracket.

Fig. 7 is an end view of the supporting bracket for the spring.

Fig. 8 is a transverse section on the line 8—8 of Fig. 6.

The compressor consists of a base 1 having the supporting beam 2 mounted upon the same. The upper surface 3 of this beam is provided with a notch 4 which is shown in detail in Fig. 5 and which is so arranged as to receive a usual supporting bracket 5 attached to a coil spring 6 utilized as a shock absorber for an automobile.

An upright 8 shown as a channel bar is mounted upon base 1 beyond one end of beam 2. Angle irons 9 are pivoted at 10 to the respective sides of channel bar 8 so as to extend rearwardly above beam 2. These angle irons, preferably, taper away from one another toward their rear ends and may be connected at desired points by cross bars 12. One side of each of the angle bars is positioned substantially vertically, and the other side of each of the angle bars extends in-

wardly from the vertical side so that the angle bars may engage opposite sides of the spring 6 with the inwardly extending sides of the bars resting upon the top of the 60 spring, as clearly shown in Fig. 1.

Locking means is provided for retaining the angle bars in different depressed positions. For this purpose a bar 13 is pivoted at its lower end in the rear end of beam 2 65 as shown at 14. The bar extends upwardly between the angle bars 9 and is provided with a notched edge 15 adapted to engage one of the cross bars 12 connecting angle bars 9 in any one of said notches so as to retain the 70 angle bars in adjusted positions.

When the spring to be compressed is mounted upon its usual bracket 5, said bracket is received in the notch 4 with the spring extending upwardly between the angle bars 9 and the inwardly extending sides of said bars resting against the top of said spring. The locking bar 13 is then swung inwardly so as to disengage cross bar 12 and the spring is compressed to any desired 80 degree by the operator placing his weight upon the rearwardly extending outwardly flared ends of angle bars 9. This is, preferably, accomplished by the operator sitting upon said angle bars.

When the spring has been compressed the desired amount, locking bar 13 is swung toward cross bar 12 so that the latter is engaged in one of the notches 15. The spring will then be held in its compressed condition and a usual retaining bolt 18 may be inserted through the coils of the spring and connected to bracket 5 in usual manner. The usual cross plate 19 upon bolt 18 is then positioned against the upper end of the compressed spring, as clearly shown in Fig. 2, by means of the nut 20 screwed downwardly upon bolt 18 against said cross plate. The compressed spring may then be removed by releasing the angle bars and swinging the latter upwardly.

In Fig. 1 is shown the method of compressing a spring which has been detached from its bracket 5. For this purpose a plate such as shown in Fig. 4 and comprising a 105 disc 22 is positioned at the base of the spring which is to be compressed. The disc is inserted between the lowermost coils of the spring until an arcuate flange 23 provided upon said disc abuts against a coil of the 110 spring. The disc is provided with an axial opening 24 to receive the retaining bolt 18

and said opening is provided with opposite slots 25 through which the pin 26 upon the lower end of bolt 18 may be received. After the pin 26 has been received through slots 5 25 the bolt 18 is turned so that said pin will impinge against the lower surface of disc 22 and thereby prevent removal of the bolt.

It will be understood that bolt 18 extends 10 upwardly through the coils of the spring as previously described, and that the cross plate 19 and nut 20 are positioned upon the upper end of the bolt so that when the spring is compressed the cross plate may be 15 screwed down against the upper end of the spring by means of the nut.

The spring with the mechanism, as thus described for retaining it in compressed position, is mounted upon the upper surface 20 of beam 2, preferably, above notch 4 and the spring is then compressed by means of the angle bars as previously described. When the spring has been sufficiently compressed and the angle bars have been locked 25 in position by means of bar 13 the spring may be secured in compressed position by screwing nut 20 downwardly, as previously described.

While I have illustrated the improved 30 spring compression as employed in connection with springs used as shock absorbers, it will be readily apparent that the device is adapted for general use, and may be advantageously employed whenever it is desired to compress various types of springs.

Various changes may be made without departing from the spirit of the invention as claimed.

What is claimed is:

40 1. A spring compressor including a base for supporting a spring, a lever connected

to said base so as to engage said spring for compressing the latter and a ratchet bar pivotally mounted on the base and adapted to engage a part of said lever when the same 45 is depressed to compress a spring positioned on said base.

2. A spring compressor including a base for supporting a spring, said base being notched in order to accommodate a spring 50 supporting bracket, a lever connected to said base so as to engage said spring for compressing the latter, and a pivotally mounted ratchet bar for locking said lever in pivotally adjusted positions.

3. A spring compressor including a base, a spring supporting plate adapted to be removably position on said base, a frame pivotally connected to the base and including a pair of arms that are adapted to engage the 60 top of a spring positioned on said plate, and means for retaining said frame in its depressed spring compressing position.

4. A spring compressor including a spring supporting plate adapted to be inserted between the coils of said spring, clamping means secured to said plate for holding the spring in compressed position, a base upon which said spring, supporting plate and clamping means are mounted, and a lever 70 connected to said base so as to engage said spring for compressing the same.

5. A spring compressor including a base for supporting a spring, said base being notched to receive the supporting means for 75 said spring, and a lever connected to said base so as to engage said spring for compressing the same.

In testimony whereof I have signed my name to this specification.

HOWARD H. DOUGLASS.
